UNITED STATES PATENT OFFICE.

RALPH E. STONE, OF OSWEGO, NEW YORK.

FRUIT-BLEACHER.

SPECIFICATION forming part of Letters Patent No. 281,940, dated July 24, 1883.

Application filed March 27, 1883. (No model.)

To all whom it may concern:

Be it known that I, RALPH E. STONE, of Oswego, in the county of Oswego, in the State of New York, have invented new and useful 5 Improvements in Fruit-Bleachers, of which the following, taken in connection with the accompanying drawings, is a full, clear, and exact description.

This invention consists, essentially, in the 10 construction of a chamber provided at its base with a fumigant-receptacle, a fruit-rack over the same, and a fume-exit above the rack, by which arrangement the fruit deposited on the aforesaid rack becomes effectually bleached in 15 in a most convenient, reliable, and expeditious manner.

The invention also consists in the combination, with the aforesaid apparatus, of certain auxiliary devices, all as hereinafter fully 20 described, and specifically set forth in the claims.

In the annexed drawings, Figure 1 is an isometric view of my improved fruit-bleacher. Fig. 2 is a vertical transverse section; Fig. 3, 25 a vertical longitudinal section. Fig. 4 is a horizontal section on line *x x* in Fig. 3; and Fig. 5 is a horizontal section on line *y y*, Fig. 3.

Similar letters of reference indicate corresponding parts. 30 A A represent two square or rectangular chambers placed adjacent to each other and separated by the vertical partition P. The bottom of each of said chambers is provided with a port, *a*, over which is placed a slide, *s*, 35 which is extended through a port, *c*, in the base of the partition P and in line with the two ports *a a*. A lever, *l*, connected with said slide and projecting through the side of the chamber A, allows the slide *s* to be shifted, so 40 as to open one port, *a*, while closing the other, two stops or gates, *f f*, being secured to the slides in such relative positions as to encounter the opposite sides of the partition at the proper time to arrest the movement of the 45 slide and simultaneously close the port *c* in the partition.

b designates a receptacle for the sulphur, by the combustion of which the requisite fume is generated for bleaching the fruit, said receptacle being secured to the slide *s*, so as to cause 50 it to be transferred from one chamber to the

other simultaneously with the opening and closing of the ports *a a*, as hereinbefore described, the fumigant-receptacle *b* being carried into that chamber A in which the bleaching 55 process is to be carried on, and in so transferring said receptacle the port *a* in said chamber is closed to exclude the air, while the port of the other chamber is opened to admit a current of air for the purpose of cooling and ventilating 60 the same preparatory to removing the bleached fruit and introducing a new supply to be bleached.

R denotes an oscillatory rack, formed of slats, secured at or near their center cross-wise to a bar which is mounted in suitable bearings on opposite sides of the chamber, and is adapted to rock or turn thereon, one end of said bar protruding through the side of the chamber, and being provided at the exterior 70 thereof with a suitable handle, *m*, by which to shake or tilt the rack. By means of a cleat, *o*, fixed to one of the inner sides of the chamber, the rack R is supported in a horizontal position, and another cleat, *o'*, fixed at the opposite inner side some distance below the level of the rack, serves to limit the rocking or tilting motion of the rack. Along the top of the cleat *o'* an opening is formed in the side of the chamber, which opening is closed by a door, 80 D. The described rack is designed to support 75 whole fruit to be bleached, which is introduced by the means and in the manner hereinafter described. After the bleaching is accomplished the rack can be tilted and caused 85 to deliver the fruit through the opened door D and into a suitable receptacle placed on the outside of the chamber.

Above the rack R, I place in the chamber A a drawer, *d*, which has a perforated or slotted 90 bottom to allow the fumes to pass through it, said drawer being designed for the reception of sliced fruit to be bleached, and being made removable from the chamber, to admit of a better disposition or distribution of the fruit 95 in said drawer.

The top T of the two chambers A A, I provide with two apertures, *g g*, one for each chamber, and over said apertures I superstruct a flue, *F*, by means of which said chambers 100 communicate with the ventiduct or fume-exit E. The side of the flue *F* is provided with

two openings, $r r$, directly opposite the two apertures $g g$ aforesaid, and these openings rr are closed from the inside of the flue by doors $h h$, hinged at their top edge above the said openings. i denotes a chute fitted to enter the opening r , and formed with an inclined bottom and with vertical sides, having their inner end, n , beveled, so that by pushing the chute into the opening r the sides of the chute will crowd to the door h inward and upward, and thus automatically open the same.

The fruit to be bleached is taken direct from the fruit-dresser or paring-machine to the bleacher, so as to avoid exposing the fruit to the air as much as possible. It is introduced through the chute i , from whence it passes through the apertures g down to the drawer d or rack R . So soon as this is accomplished the chute is withdrawn, when the door h will drop and automatically close the opening r , to prevent the escape of the fumes through the same.

Having described my invention, what I claim as new, and desire to secure by Letters Patent, 25 is—

1. In a fruit-bleacher, the combination of a chamber provided with a door in its side, a fumigant-receptacle at the base of the chamber, an oscillatory fruit-rack over the fumigant-receptacle, and communicating at its lower edge with the side door of the chamber and a fume-exit above the fruit-rack, substantially as described.

2. The combination of the chamber A, provided at its base with the ports $a a$ and valve s , and with the fumigant-receptacle b , the door D , arranged in the side of the chamber, the rack R , adapted to rock toward said door, and a ventiduct applied to the top of the chamber,

substantially as and for the purpose shown 40 and set forth.

3. The combination of the chamber A, provided with the ports $a a$ and valve s , fumigant-receptacle b , and door D , the oscillatory rack R , perforated or slotted drawer d , and ventiduct E , substantially as shown. 45

4. The combination, with the chambers A A, placed adjacent to each other and provided, respectively, with racks $R R$ and a ventiduct, E , the partition P , provided with the port e , the bottom B , provided with ports $a a$, and the slide s , provided with the stops $f f$ and with the fumigant-receptacle b , substantially in the manner described and shown. 50

5. In combination with the bleaching-chambers A A, the top T , provided with the apertures $g g$, the superstructed flue F , extended over said apertures and provided with doors $h h$, and the chutes $i i$, adapted to enter said doors, substantially as described and shown, 60 for the purpose set forth.

6. In combination with the bleaching-chambers A A, provided at the top with the apertures $g g$, the superstructed flue F , provided with the exit E and having openings $r r$, with 65 the doors $h h$, hinged at their top edge, and the chute i , having its sides formed with the beveled ends n , substantially as described and shown.

In testimony whereof I have hereunto signed 70 my name and affixed my seal, in the presence of two attesting witnesses, at Syracuse, in the county of Onondaga, in the State of New York, this 7th day of March, 1883.
